CLAIM

The ornamental design for a contact module for a firearm accessory, as shown and described.

DESCRIPTION

FIG. 1 is a bottom isometric view of a first embodiment of the contact module for a firearm accessory according to the present disclosure;

FIG. 2 is a top isometric view thereof;

FIG. 3 is another top isometric view thereof;

FIG. 4 is a front view thereof;

FIG. 5 is a rear view thereof;

FIG. 6 is a right view thereof;

FIG. 7 is a left view thereof;

FIG. 8 is a bottom view thereof;

FIG. 9 is a top view thereof;

FIG. 10 is a bottom isometric view of a second embodiment of the contact module for a firearm accessory according to the present disclosure;

FIG. 11 is a top isometric view thereof;

FIG. 12 is another top isometric view thereof;

FIG. 13 is a front view thereof;

FIG. 14 is a rear view thereof;

FIG. 15 is a right view thereof;

FIG. 16 is a left view thereof;

FIG. 17 is a bottom view thereof; and,

FIG. 18 is a top view thereof.

The evenly spaced dashed lines in the Figures depict portions of the contact module for a firearm accessory that form no part of the claimed design.

The dot-dash lines represent a boundary of the claimed design, and form no part of the claimed design.
